(Cl. D58—13)

To all whom it may concern:

Be it known that I, Thomas R. Polglase, a citizen of the United States, residing at R. R. #2, Spring Lake, county of Ottawa, State of Michigan, have invented a new, original, and ornamental Design for a Shipping Case, of which the following is a specification, reference being had to the accompanying drawing, forming a part hereof.

Fig. 1 is a top plan view of a shipping case showing my new design;

Fig. 2 is a side elevation thereof;

Fig. 3 is an end elevation thereof; and

Fig. 4 is a perspective thereof with the top raised and taken on a reduced scale.

I claim:

The ornamental design for a shipping case, as shown.

THOMAS R. POLGLASE.
